United States Patent Office

Des. 216,232
Patented Dec. 2, 1969

216,232

CHECK-OUT COUNTER

Morris Stackhouse, Wayne, Pa., assignor to Penn Fruit
Co., Inc., Philadelphia, Pa., a corporation of Delaware

Filed Jan. 14, 1969, Ser. No. 15,348

Term of patent 14 years

Int. Cl. D6—01

U.S. Cl. D80—2

Fig. 1

I claim:

The ornamental design for check-out counter, substantially as shown and described.
